UNITED STATES PATENT OFFICE

THOMAS C. McBRIDE, OF PHILADELPHIA, PENNSYLVANIA, ASSIGNOR TO WORTHINGTON PUMP AND MACHINERY CORPORATION, OF NEW YORK, N. Y., A CORPORATION OF VIRGINIA

FEED WATER HEATER

Application filed September 10, 1930. Serial No. 480,841.

This invention relates to feed water heating apparatus and more especially to feed water heaters of the type disclosed in my companion application filed June 4th, 1926, Serial No. 113,620.

An object of the present invention is to provide in a feed water heating apparatus means controlled by the over-flow of excess water from the heating chamber for controlling the supply of fresh or cold water to the heating chamber.

The invention comprehends the provision of a return or excess water pump which returns the varying excess of water due to steam condensation, to the heating chamber of the apparatus having associated therewith a suitable valve mechanism operated by the pressure of the discharge of the return or excess water pump, which valve mechanism, in turn, controls the supply of cold water to the heating chamber by controlling the discharge from the cold water supply pump.

With these objects in view, the invention consists in various features of construction and combination of parts, which will be first described in connection with the accompanying drawings, showing a feed water heater of the preferred form embodying the invention, and the features forming the invention will be specifically pointed out in the claims.

In the drawings—

Figure 1 is a vertical section through the feed water heater showing the improved cold water supply control means associated therewith.

Figure 2 is a fragmentary section through the feed water heating apparatus taken on the line 2—2 of Figure 1.

Referring more particularly to the drawings, the improved feed water heating apparatus comprises the heating chamber 1 into which the cold water is delivered by the sprayer 2 and in which the cold water entering the chamber in sprays contacts with steam, preferably the exhaust steam from a steam engine or other mechanism which enters the chamber 1 through the passageway 3.

The supply of cold water is from any suitable reservoir or container (not shown) through the pipe 4 to the suction of the cold

water supply pump 5 which is illustrated as a centrifugal pump. The cold water supply pump 5 discharges through the pipe or passageway 6 into the passageway 7 formed in the casting or housing 8 of the control mechanism. A plunger or piston valve 9 is mounted within the bore of the housing 8 which, when in its lowered position opens communication between the passageway 7 and the opening 12 to permit the cold water to pass through the control valve mechanism, and into the chamber 13 which delivers the cold supply water to the sprayer 2. The valve piston 9 is urged into its downward position, to permit the flow of cold water into the chamber 13, by a spring 14 the tension of which may be regulated by a suitable manually operated tensioning device 15 of any approved construction.

Owing to variances in the condensation of steam in the chamber 1 a varying quantity of excess water will be provided in the chamber 1 and to prevent impairment of the efficiency of the operation of the heater by an accumulation of excess water in the heater, and maintain a constant water level therein, an over-flow pipe 16 is provided which rises in the chamber 1 and into which any excess of water flows. The excess water passes through the over-flow pipe 16 to the suction or inlet of a return pump 17 which returns this excess water to the heating chamber through its inlet, thereby preventing the loss of the heat which has been absorbed by the excess water as well as preventing the waste of such water. The return pump 17 discharges into a chamber 18 and through a check valve 19 into the passageway 13. The chamber 18 has a lateral extension 20 which extends beneath the piston 9 of the cold water supply control valve structure so that the pressure of the return water will act on the piston 9 against the tension of the spring 14 to move the piston 9 for controlling the quantity of cold water delivered to the passageway 13.

When the water level is low in the heating chamber 1 there will be no water over-flow to the return pump 17 and its discharge pressure will be low which will permit the valve piston 9 to move under action of the spring 14 and permit an

increased flow of supply water from the cold water supply pump 5 to the heating chamber 1.

A check valve 21 is provided at the communication between the pipe 6 and passageway 7 which prevents the back-flow of water through or to the supply pump 5 when there is a high pressure of exhaust steam in the chamber 1 and the pumps are not operating. The 10 check valve 19 prevents cold water being pumped into the heater from being forced through the chamber 18 into the pump 17 when the quantity of excess water falls below the amount required to supply such water to 15 the pump 17.

A pipe 22 communicates with the interior of the bore or valve chamber of the housing 8 and with the interior of the chamber 1, preferably at the top of said chamber so as to permit any water which might leak past the 20 valve piston or plunger 9 to pass into the heating chamber and be heated.

From the foregoing description taken in connection with the accompanying drawings, 25 it will be apparent that a control mechanism has been provided by means of which the quantity of over-flow of excess water from the heating chamber 1 of the heater will control the supply of cold water to the heating 30 chamber; the supply of cold water being regulated in reverse proportion to the quantity of over-flow of excess water returned to the heater in that the movement of the valve piston or plunger 9 will be regulated by the 35 pressure of the returning over-flow water.

It will be understood that the invention is not to be limited to the specific construction or arrangement of parts shown but that these may be modified widely within the invention 40 defined by the claims.

What is claimed is:

1. In a feed water heating apparatus, a heating chamber, means for supplying cold water to said heating chamber, means for returning excess water to the heating chamber 45 and means operated by the returning excess water for controlling the supply of cold water to the heating chamber.

2. In a feed water heating apparatus, a heating chamber, means for returning excess water from the heating chamber to the inlet 50 of the heating chamber and means operated by the pressure of the returning excess water for controlling the supply of cold water to the heating chamber.

3. In a feed water heating apparatus, a heating chamber, means for returning excess water from the heating chamber to the inlet of the heating chamber and a valve operated 60 by the pressure of the returning excess water for controlling the supply of cold water to the heating chamber.

4. In a feed water heating apparatus, a heating chamber, means for returning the 65 overflow of excess water from the heating

chamber to the inlet of the heating chamber, a valve operated by the pressure of the returning excess water for controlling the supply of cold water to the heating chamber, and a check valve for preventing backward flow 70 of cold water to said means when no excess water is being returned to the heating chamber.

5. In a feed water heating apparatus, a heating chamber, a return pump for delivering over-flow of excess water from the heating chamber to the inlet of the heating chamber, a valve for controlling the supply of cold water to the heating chamber, means for urging said valve to open position to permit the 75 flow of cold water to the heating chamber, said valve being acted upon by the pressure of the returning excess water to move it for regulating the supply of cold water in inverse proportion to the quantity of returned 80 excess water.

6. In a feed water heating apparatus, a heating chamber, a centrifugal pump for supplying cold water to said chamber, means for returning excess water from the heating chamber to the inlet of the heating chamber and means operated by the pressure of the returning excess water for controlling the quantity of cold water supplied by said 90 centrifugal pump.

7. In a feed water heating apparatus, a heating chamber, a cold water supply pump and a return pump for taking excess water from the heating chamber and returning it to the inlet of the heating chamber, and means operated by the pressure of the excess water as discharged from said return pump for controlling the quantity of water delivered to the heating chamber by said cold water supply pump.

8. In a feed water heating apparatus, a heating chamber, a cold water supply pump and a return pump for taking excess water from the heating chamber and returning it to the inlet of the heating chamber, a valve 100 for controlling the quantity of water delivered to the heating chamber by said cold water supply pump, said valve being acted upon by the water discharged by said return pump for regulating the quantity of cold water delivered to the heating chamber in inverse proportion to the quantity of excess water returned to the heater.

9. In a feed water heating apparatus, a heating chamber, a cold water supply pump and a return pump for taking excess water from the heating chamber and returning it to the inlet of the heating chamber, a valve for controlling the quantity of water delivered 110 to the heating chamber by said cold water supply pump, said valve being acted upon by the water discharged by said return pump for regulating the quantity of cold water delivered to the heating chamber in inverse proportion to the quantity of excess water returned to the heater.

10. In a feed water heating apparatus, a heating chamber, a cold water supply pump and a return pump for taking excess water from the heating chamber and returning it to the inlet of the heating chamber, a valve for controlling the quantity of water delivered 120 to the heating chamber by said cold water supply pump, said valve being acted upon by the water discharged by said return pump for regulating the quantity of cold water delivered to the heating chamber in inverse proportion to the quantity of excess water returned to the heater.

turned to the heater, and means for urging said valve into position to permit the maximum quantity of cold water to be delivered to said heating chamber.

5 10. In a feed water heating apparatus, a heating chamber, a cold water supply pump and a return pump for taking excess water from the heating chamber and returning it to the inlet of the heating chamber, a valve for controlling the quantity of water delivered to the heating chamber by said cold water supply pump, said valve being acted upon by the water discharged by said return pump for regulating the quantity of cold water 10 delivered to the heating chamber in inverse proportion to the quantity of excess water returned to the heater, a check valve for preventing backflow of water through said cold water supply pump, and a second check valve 15 in the path of discharge of said return pump.

In testimony whereof I affix my signature:
THOMAS C. McBRIDE.
